DESIGN FOR A SHOE

Max Kagan, Old Town, Maine, assignor to Penobscot Shoe Company, Old Town, Maine, a corporation of Maine

Application April 4, 1947, Serial No. 138,161

Term of patent 3½ years

(Cl. D7—7)

To all whom it may concern:

Be it known that I, Max Kagan, a citizen of the United States, residing at Old Town, county of Penobscot, State of Maine, have invented a new, original, and ornamental Design for a Shoe, of which the following is a specification, reference being had to the accompanying drawing, forming a part thereof.

In the drawing:

Fig. 1 is a top perspective view of a shoe, showing my new design;

Fig. 2 is a side perspective view of the same;

Fig. 3 is a top plan view of the same.

I claim:

The ornamental design for a shoe, substantially as shown.

MAX KAGAN.
